US00D953254S

(12) **United States Design Patent** (10) **Patent No.:** **US D953,254 S**
(45) **Date of Patent:** **** May 31, 2022**

(54) **BATTERY MODULE**

(71) Applicant: **Transportation IP Holdings, LLC**,
Norwalk, CT (US)

(72) Inventors: **Patrick Lee Jansen**, Schenectady, NY
(US); **Neil Bradley**, Erie, PA (US);
Gregory Badders, Erie, PA (US);
Michael Jay Grutkowski, Erie, PA
(US)

(73) Assignee: **Transportation IP Holdings, LLC**,
Norwalk, CT (US)

(**) Term: **15 Years**

(21) Appl. No.: **29/775,481**

(22) Filed: **Mar. 23, 2021**

Related U.S. Application Data

(62) Division of application No. 29/693,882, filed on Jun.
5, 2019, now Pat. No. Des. 919,561, which is a
division of application No. 29/595,064, filed on Feb.
24, 2017, now Pat. No. Des. 855,562.

(57) **CLAIM**

The ornamental design for a battery module, as shown and
described.

DESCRIPTION

FIG. 1 is a perspective view of a battery module depicting
our new design;

FIG. 2 is a top plan view thereof;

FIG. 3 is a bottom plan view thereof;

FIG. 4 is a front view thereof;

FIG. 5 is a rear view thereof;

FIG. 6 is a side view thereof; and,

FIG. 7 is an opposite side view thereof.

In the drawings, the broken lines illustrate portions of the
article that form no part of the claimed design.
